UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 14,872, dated March 11, 1884.

Application filed January 28, 1884. Term of patent 3½ years.

To all whom it may concern:

Be it known that I, OTTO HEINIGKE, of New Utrecht, in the State of New York, have invented a new and original Design for Carpets, 5 of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

15 The feature of the design is its peculiar paneling. The panels are rarely complete in outline; but the outlines so far as they appear are

conspicuous, and are spiral, curvilinear, scalloped, lichen-like, and right-lined, as fully shown in the photograph. The ornamentation of the different panels is various, leaf-clusters and blossom-sprays predominating, some of the clusters showing full leaves massed over shadow-leaves. The large flower group of the design is shown at the upper and lower centers of the photograph.

I claim—

The design for a carpet, substantially as shown and described.

OTTO HEINIGKE.
